PRESSURE FLUID MOTOR

Elmer G. Gartin, Claremont, N. H., assignor to
 Sullivan Machinery Company, a corporation
 of Massachusetts

Application November 1, 1934, Serial No. 751,009

4 Claims. (Cl. 121—12)

This invention relates to pressure fluid motors, and more particularly to improvements in the control valve mechanism of such motors.

An object of this invention is to provide an improved pressure fluid motor. Another object is to provide an improved fluid distribution means for such a motor having embodied therein improved and simplified fluid distributing valve mechanism. A further object is to provide an improved fluid distributing valve mechanism having embodied therein improved throttle control means. Yet another object is to provide an improved fluid supply connection associated with the fluid distributing valve mechanism. Still another object is to provide an improved controlling mechanism for a percussive motor whereby a variable blow may be obtained. These and other objects and advantages will, however, hereinafter more fully appear.

20 In the accompanying drawing there is shown for purposes of illustration one form which the invention may assume in practice.

In this drawing,—

Fig. 1 is a longitudinal sectional view through the illustrative form of the improved pressure fluid motor.

Fig. 2 is a view similar to Fig. 1 showing the moving motor parts in a different position.

Fig. 3 is a detail sectional view taken on line 30 3—3 of Fig. 1.

Fig. 4 is an end elevational view of the valve chest element.

Fig. 5 is an elevational view of the fluid distributing valve.

35 In this illustrative construction there is shown a pressure fluid motor comprising a cylinder 1 having a bore 2 containing a reciprocating hammer piston 3. The hammer piston has a piston head 4 fitting the cylinder bore and a forwardly projecting cylindrical striking bar 5 for delivering impact blows to the shank of a suitable working implement 6, the striking bar being guided in a bore 7 formed in the front motor head 8. The working implement is supported 40 within a suitable chuck 9 carried by a chuck housing 10. The rear end of the cylinder bore is closed by a rear head block 11. The parts 8, 10 and 11 are held in assembled relation with respect to the cylinder in any suitable manner.

50 Now referring to the improved fluid distribution means, it will be noted that formed in the rear head member 11 is a transverse bore 14 arranged with its axis extending at right angles with respect to the cylinder bore axis, and 55 arranged in this bore is a cylindrical valve chest element 15 held therein by a screw plug 16. Aligned with the bore 14 is a reduced bore 17 having arranged therein a cylindrical valve control member 18. Swivelly mounted in a conical bore 19 formed in the plug 16 and coaxial with

the valve chest bore is a fluid supply connection 20, and the plug 16 has an inner chamber 21 for receiving fluid from the connection 20 from any suitable pressure fluid source. In the inner face of the element 15 is a bore 22 forming a valve chamber in which is reciprocably mounted an automatic fluid distributing valve 23, herein of the relatively thin, flat disc type. The inner face of the member 15 is multi-arcuately recessed at 24, at the periphery of the bore 22, 10 having intermediate shoulders 24' to guide the valve 23, and the recesses 24 are connected through passages 25 with the fluid supply chamber 21 in the plug 16, while the inner wall of the bore 14 is annularly recessed at 26. The inner 15 face of the member 15 and the inner wall of the bore 14 are annularly grooved at 27 and 28, respectively, these grooves being arranged concentrically within the outer recesses 24, 26. The groove 28 is connected to one passage 25 through a passage 29, while the recess 26 is connected to the groove 27 through a passage 30. Formed centrally within the member 15 and communicating with the valve chamber is a bore 31 connected through a passage 32 with a recess 33 25 communicating directly with the rear end of the cylinder bore. The valve control member 18 is provided with a central bore 34 communicable through a radial port 35 with an annular recess 36 surrounding the bore 17, and this recess is 30 connected through a passage 37 and port 38 with the forward end of the cylinder bore. The cylinder is provided with a piston controlled, centrally located free exhaust port 39.

When the parts are in the position shown in Fig. 1, pressure fluid may flow through the swivel connection 20, groove 21, passages 25, recesses 24, through the valve chamber past the outer face of the valve 23, bore 31, passage 32 and chamber 33 to the rear end of the cylinder bore, 40 the pressure fluid acting on the rear pressure area of the motor piston to drive the latter forwardly to effect its working stroke, i. e., to deliver an impact blow to the shank of the working implement 6. As the motor piston moves forwardly, the piston head 4 closes the central exhaust port 39, and upon continued forward movement of the piston, the rear edge of the piston head overruns the exhaust port 39, thereby connecting the rear end of the cylinder bore to exhaust, and as a result, there is a material reduction in pressure in the valve chamber at the outer side of the valve. The constant pressure in groove 27 acting on the inner face of the valve together with the compression pressure built up in chamber 34, then throws the valve forwardly against the opposing reduced pressure, from the position shown in Fig. 1 to the position shown in Fig. 2. Pressure fluid then flows through passage 25, recess 26, through the valve chamber past the inner 50 55 60 65 70 75 80 85 90 95 100 105 110 115 120 125 130 135 140 145 150 155 160 165 170 175 180 185 side of the valve, through the bore 34 in the valve 18, and through port 35, recess 36, passage 37 and port 38 to the forward end of the cylinder bore, the pressure fluid acting on the forward pressure area of the piston to drive the latter rearwardly. As the motor piston moves rearwardly the piston head closes the exhaust port 39, and upon continued rearward movement of the motor piston, the forward edge of the piston head overruns the free exhaust port 39, thereby connecting the front end of the cylinder bore to exhaust; and as a result there is a material reduction in pressure in passage 37, bore 34 and in the valve chamber at the inner side of the 15 valve. The constant pressure in groove 28 acting on the outer face of the valve, plus the compression pressure in chamber 31, overcomes the opposing reduced pressure and throws the valve inwardly from the position shown in Fig. 2 to the 20 position shown in Fig. 1. These operations are rapidly repeated during normal operation of the motor.

Associated with the fluid distributing valve is the improved throttle control means comprising 25 the valve control member 18. The member 18 is threaded at 43 within the head member 11, and is provided with an operating handle 44. When it is desired to throttle the motor, the operator grasps the handle 44 and rotates the member 30 18, thereby moving the latter axially inwardly so that the inner end thereof engages the inner face of the valve 23, moving the valve tightly against its outerseat in the position shown in Fig. 2, the inner end of the member 18 at the same 35 time having tight end surface contact with the inner surface of the valve. As a result, the distributing valve is held in the position in Fig. 2 while the inner end of the member 18 tightly engages the inner face of the distributing valve. 40 The parts when in this position close off communication of the fluid supply passage 25 with the bores 31 and 34, thereby cutting off supply of pressure fluid to the motor. When the member 18 is rotated to the position shown in Fig. 45 2, the distributing valve is free to operate in its normal manner.

It will further be noted that if the sleeve-like right-hand extremity of the member 18 be not projected far enough to the right in Fig. 1 to 50 hold the valve 23 stationary, but simply be caused to project a few hundredths of an inch, for example, inwardly beyond that portion of the bottom of the valve chest chamber which is surrounded by the inner wall of the groove 27, there 55 will be provided continued operation of the motor, but with reduced force of blow, and a tendency toward shortstroking. It is true that there will be an increased constant pressure differential, so to speak, at the left hand end of the valve, but 60 this will not be adequate to preclude the normal automatic operation of the valve, although it will vary the instant of movement of the valve from left to right position, as from that in Fig. 1 to that in Fig. 2. Accordingly since this increased differential area will speed up the throw 65 of the valve with respect to the forward stroke of the piston, a very beneficial result is obtained by my invention in the blow lightening function which can be obtained in the manner described.

As a result of this invention, it will be noted that an improved fluid distribution means is provided which is of an extremely simple design, the

improved fluid distribution means having associated therewith an improved fluid supply connection so that a substantially direct fluid supply to the valve chamber is attained. It will further be noted that by associating the throttle valve control element with the distributing valve the throttle controlling function of the motor is greatly simplified. Moreover it will be observed that a very simple and effective means for varying the blow and the piston travel is provided. These and other uses and advantages of the improved pressure fluid motor will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a pressure fluid motor, a cylinder having a piston reciprocable therein, and fluid distribution means for effecting reciprocation of said piston including a fluid actuated distributing valve, means for subjecting an area on said valve to a throwing pressure, and means for changing said effective area on which the throwing pressure acts to alter the time of valve throw.

2. In a pressure fluid motor, a cylinder having a bore, a piston reciprocable therein, fluid distribution means for effecting reciprocation of said piston including an automatic fluid actuated fluid distributing valve, throttle means associated with said valve and engageable with the latter to move said valve into a position to close completely the supply of pressure fluid past said valve to said cylinder bore, and abutment means relative to which said throttle means is adjustable for limiting movement of the valve in opposite directions during the normal fluid distributing function of the valve and when said throttle means is moved out of the path of normal valve travel.

3. In a pressure fluid motor, a cylinder having a hammer piston reciprocable therein, and fluid distribution means for effecting reciprocation of said piston including a fluid actuated fluid distributing valve, stop means for limiting movement of said valve in opposite directions during its normal operation, and adjustable control means associated with said valve and movable relative to said stop means, said control means engageable with said valve at one side thereof to effect varied ranges of movement of said valve to control the force of the piston blow.

4. In a pressure fluid motor, a cylinder having a hammer piston reciprocable therein, and fluid distribution means for effecting reciprocation of said piston including a fluid actuated fluid distributing valve, stop means for limiting movement of said valve during its normal operation, and adjustable control means associated with said valve and movable relative to said stop means, said control means engageable with said valve at one side thereof to effect varied ranges of movement of said valve to control the force of the piston blow, one of said stop means having a central bore and said control means being movable in said central bore.

ELMER G. GARTIN.
